UNITED STATES PATENT OFFICE

1,951,459

TROLLEY SLIDE

**Kenneth M. Wilkins, Waukegan, Ill., assignor to
Superior Trolley Slide & Equipment Company,
Waukegan, Ill., a corporation of Illinois**

Application January 27, 1932, Serial No. 589,146

8 Claims. (Cl. 191—59.1)

My invention relates generally to current collecting devices and particularly has to do with a device which is adapted to slidably engage a trolley wire or other conductor to collect or obtain current therefrom.

Devices of the character above referred to are generally secured adjacent the end of a trolley pole and consist of a body member to which is pivotally secured a carrier member 10 preferably provided with a removable insert or shoe member.

One of the principal objects of my invention is to design and construct a device in which a portion or member thereof may be easily and 15 quickly loosened or removed so as to detachably secure a carrier member.

It is also an object of my invention to provide recesses for the means employed in securing the arm members or portions together so that 20 the means do not extend or project beyond the confines of the body member or support.

A further object of my invention is to provide a device in which the insert or shoe member carried by the carrier member is located in close 25 proximity to the pivotal axis of the means employed in connecting the carrier to the support, the advantage of which insures more efficient frictional contact between the insert and trolley wire.

30 Another object is to design and construct the carrier member with integral transverse projecting portions which provide a pivotal connection between the carrier and the support.

A still further object of my invention is to 35 design and construct a device which is very substantial and durable.

Many other objects and advantages of my invention will appear after considering the following description in connection with the drawing 40 annexed hereto.

With reference to the drawing wherein the parts of the device are designated by numerals, Fig. 1 is a side view of the current collecting device showing the general arrangement of its several elements or parts;

Fig. 2 is a section taken substantially on line 2—2 of Fig. 1;

Fig. 3 is a section taken substantially on line 3—3 of Fig. 1; and

Fig. 4 is a section taken through a portion of the carrier member.

Considering the several figures disclosed in the drawing, it will be evident that the body member is generally designated 1 and is preferably designed to be secured adjacent the end of a trolley

pole. The member which is designed to receive the removable insert or shoe member is generally designated 2 and as shown is pivotally secured with respect to the body member generally designated 1. As shown in Fig. 2 the body member 1 is 60 provided with an integral arm portion 3, and a side portion or member 4 is adapted to be detachably connected or associated with respect to the body member and integral side portion 3. The end such as 3' of the removable side portion is 65 preferably rounded and seated in a recess such as 1', so that the exposed face of the side portion is flush with the side of the wall of the body. The integral arm portion 3, is provided with an integral projection or circular boss portion 5, the extreme end being adapted to extend into the recess or aperture 7 and abut wall 7' provided in the integral projection or boss portion 8 formed on the removable side member 4; which arrangement 70 will provide means for gauging the space between 75 the arm portions. A hole or aperture 9 is provided in the boss portion 5 of the integral side portion 3 and an aperture of the same diameter is provided in the boss portion 8 of the removable side member 4. A bolt such as 11 provides means for 80 cooperatively securing the said side portions or arm members together. As above stated, one of the important objects of my invention is to arrange the locking means or in other words, the bolts, in a position so that they do not extend beyond the confines of the arms and this is accomplished by providing recesses 12 and 13 in the arms, which respectively receive the head and nut of the bolt 11. The removable side member 85 or arm 4 is also secured to the body portion of the support; and as clearly shown in Fig. 3, is provided with an inwardly extending boss portion 14 which is located in a recess 14' provided in the body 1, and a bolt such as 15 is adapted to extend through the aperture 16 provided in the body portion and through a hole or aperture 17 provided in the boss portion 14. The body member is provided with a recess 18 and the side member 4 is provided with a recess 19 so as to respectively receive the head and nut which form a part of the 90 bolt 15 and the arrangement is therefore similar to that mentioned concerning bolt 11.

It will be evident from the description thus far, that the support for the carrier member generally designated 2 consists of a body portion 1 formed 105 with an integral extending arm portion and that a removable side portion or member is adapted to be detachably associated or connected with the body portion and integral side portion of the support, and that improved or novel means are em- 110

ployed for cooperatively securing the several parts together in a rigid and substantial manner.

The integral arm or side portion 3 of the body member and the removable side member 4, as shown, are designed to provide bearings such as 20 which are provided with apertures 21 through which means extend for pivotally connecting the carrier generally designated 2 with the support or body portion of the device. The body portion 22 of the carrier is elongated and provided with integral projections such as 23 which extend transversely of the carrier and ride in the apertures 21 of the bearings 20. It will be noted that the width of the body portion 22 of the carrier is substantially equal to the width of the bifurcation formed by the bearings 20, and therefore, there is substantially no side play or lateral movement of the carrier with respect to the support. It might be mentioned that the integral portions 23 which provide a pivotal connection between the carrier and support makes a more rigid and substantial construction. An undercut longitudinal groove is formed in the body portion 22 of the carrier and the bottom thereof is designated 24 and the walls thereof, 25. An insert or shoe member such as 26 conforming to the shape of the undercut groove is adapted to be removably mounted within said groove so as to engage the bottom and side walls thereof, and as clearly shown, and as above referred to, the insert is located in close proximity to the pivotal axis of the means providing the connection between the carrier and support. In other words it is an object of my invention to design and construct a device in which the axis of the pivotal connection is located in close proximity to the face of the insert member which is adapted to slidably engage the trolley wire, the effect of which efficiently insures a better frictional engagement or contact with the trolley wire; or in other words, there are more points of contact between the insert or shoe member and the trolley wire than there would otherwise be if the axis of the pivotal connection was at a point some distance from the face of the insert member.

The carrier member generally designated 2 is formed with upstanding side walls which are designed with concave cheek portions 28; and the removable insert member is formed to provide a longitudinal concave groove 27, which more or less conforms to the curvature of the cheek portions 28, all of which provides a longitudinal concavity which receives the trolley wire. As clearly shown in Fig. 2 the body portion 22 of the carrier is provided with a longitudinal slit or kerf 29 which obviously permits the side wall portions of the carrier to be drawn together or to be adjusted with respect to each other in a manner whereby the insert 26 may be adjusted with respect to the carrier. Each end of the insert 26 is preferably rounded as at 30 and each end of the carrier may be rounded as at 31.

The means employed for locking the insert member 26 in the undercut groove in the carrier, in the present instance, consists of a pair of bolts 32 which extend through holes or apertures such as 33 which extend transversely through the body portion 22 of the carrier, the center of each aperture being located at a point below the base 24 of the undercut groove. Formed along the bottom of the insert member adjacent each end is a transverse groove such as 34 which is designed to receive a portion of a bolt 32.

One important feature embodied in the construction and not set forth hereinbefore, is the provision of a portion or member such as 38 at

the bottom adjacent the trailing end of the carrier generally designated 2, the object of which is to provide a guard so as to prevent the cross cables supporting the trolley wire from becoming caught between the lower part of the trailing end of the carrier and the arms 3 and 4 when the car to which the trolley slide is connected is driven rearwardly.

In view of the foregoing description it will be evident that I have designed and constructed a current collecting device which consists of a body member or support and a carrier member, and that the support consists of two parts or members which are adapted to be cooperatively secured or adjusted with respect to each other in a manner to receive and support a carrier member. It will also be evident that the pivotal axis of the means providing the pivotal connection between the carrier member and the support is located at a point in close proximity to the face of the insert or shoe member, the result of which insures a more efficient contact or frictional engagement between the insert and trolley wire. In other words, the removable insert or shoe member is located in close proximity to the pivotal axis of the means employed in connecting the carrier with the support.

Having thus described my invention it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. A device of the kind described, consisting of cooperating arm portions, a carrier member and means formed integral therewith providing a pivotal connection between said carrier and said arm portions, and an insert member associated with said carrier member and located in a position whereby the pivotal axis of the connection passes through said insert member.

2. In a device of the kind described, a body member provided with an integral arm portion, an arm detachably connected to said body member and said integral arm portion, said arms providing means for supporting a carrier member, a recess provided in said body member and a boss provided on said integral arm portion, said detachable arm being provided with a boss and an aperture which respectively cooperate with the recess in said body and said boss on said integral arm portion, and means extending through said arms and body member at the places of cooperation to thereby firmly secure said detachable arm portion in position and prevent lateral movement thereof with respect to said body member and said integral arm portion.

3. A device of the kind described and set forth in claim 2, in which the body member is recessed so as to receive an end of said detachable arm portion and position the exterior face of said arm portion flush with the side of said body member.

4. A device of the kind described and set forth in claim 2, in which the arms and body member are provided with recesses for receiving the securing means in a manner whereby the latter do not extend beyond the confines of the device.

5. In a device of the kind described, a body member provided with an integral arm portion, an arm portion detachably connected to said body member and said integral arm portion, said arms

providing means for supporting a carrier member, a recess provided in said body member and a boss provided on said integral arm portion, said detachable arm being provided with a boss and an aperture which respectively cooperate with the recess in said body member and said boss on said integral arm portion, means extending through said arms and body member at the places of cooperation to thereby firmly secure said detachable arm portion in position and prevent lateral movement thereof with respect to said body member and said integral arm portion, and a guard arranged adjacent the bottom of the trailing end of said body member.

15 6. A device of the kind described and set forth in claim 5 in which the body member is recessed so as to receive an end of said detachable arm portion and position the exterior face of said

arm portion flush with the side of said body member.

7. A device of the kind described and set forth in claim 5 in which the arms and body member are provided with recesses for receiving the securing means in a manner whereby the latter do not extend beyond the confines of the device.

8. A device of the kind described, consisting of cooperating arm portions, a carrier member and means formed integral therewith providing a pivotal connection between said carrier and said arm portions, a guard arranged adjacent the trailing end of said carrier member, and an insert member associated with said carrier member and located in a position whereby the pivotal axis of the connection passes through said insert member.
